TOOL FOR CLEARING BLOCKED PIPES

Jack Samuel Conn, Surrey, England, assignor to Surrey
Steel Components Limited, Richmond, England

Filed May 24, 1971, Ser. No. 146,595

Term of patent 7 years

Int. Cl. D8—05

U.S. Cl. D8—68

Fig. 1.

Fig. 2.

Fig. 3.

Fig. 4.

Fig. 5.

FIG. 1 is a front perspective view from above and one side of the tool for clearing blocked pipes showing my new design;

FIG. 2 is a front view of the tool for clearing blocked pipes;

FIG. 3 is a rear view of the tool for clearing blocked pipes;

FIG. 4 is a view of other side of the tool for clearing blocked pipes; and

FIG. 5 is an underplan of the tool for clearing blocked pipes.

I claim:

The ornamental design for a tool for clearing blocked pipes, as shown.
